UNITED STATES PATENT OFFICE.

GILBERT S. DEY, OF MOUNT VERNON, NEW YORK, ASSIGNOR TO GENERAL OPTICAL COMPANY, INC., A CORPORATION OF NEW YORK.

WIRING SYSTEM FOR OPHTHALMOLOGICAL APPARATUS.

Application filed August 21, 1924. Serial No. 733,250.

My invention relates to ophthalmological units or apparatus which bring into one unitary, convenient assembly all of the instruments and other paraphernalia used by 5 oculists and optometrists in optical examination and treatment, and it relates more particularly to the electrical wiring system for such apparatus.

The primary object of my invention is to 10 provide such a system which will be of universal use with either alternating or direct current and with any of the usual or standard optical instruments and apparatus without danger of burning out an instrument. 15 Other objects, such as economy in current consumption and convenience in operation and control, will appear from the following detailed description of one embodiment of my invention.

20 Various voltages are required for various optical instruments, and the use of a current controller to adjust the voltage values to those suitable for the several instruments is accompanied by the danger of injuring an 25 instrument through inadvertence. With my invention the voltage supplied to the connections for the various instruments is maintained within the permissible, safe limits for all instruments of the particular class, and 30 individual provision is made for all of the usual instruments in such a way that, while all danger is eliminated, the voltage to each instrument may be varied as desired.

I shall now describe the illustrated embodiment of my invention and shall thereafter point out my invention in claims.

The drawing is a diagram of one form of wiring system embodying my invention.

I have shown my invention in a system as 10 it would be adapted to the ophthalmological apparatus forming the subject matter of the pending application of Hans Clement and myself, Serial No. 673,728, filed November 9, 1923. That application shows a unitary 15 support for various instruments which require full line voltage, such as an ophthalmometer, a refractor, and a test cabinet, and also jacks for receiving various smaller instruments that require low voltage, such as 20 an ophthalmoscope, a retinoscope and a transilluminator, as well as binding posts and receptacles of selected voltages to which other apparatus and scopes may be connected.

25 In accordance with my invention two

sockets 1 and 2 will be provided for connection of the apparatus to the line circuit, the one socket being at or near the top of the base and the other socket being near the bottom of the base. These sockets are 60 connected by wires 3 and 4 to a fuse block 5, which in turn is connected to binding posts 6 and 7 of a plate 8, which carries a switch 9, a pilot lamp 10 and a plug receptacle 11, all connected in the line by suitable wiring, not indicated. The two other binding posts 12 and 13 on the plate 8 are connected by wires 14 and 15 to the high voltage busses 16 and 17. It is, therefore, 65 evident that the full line voltage is supplied to the pilot lamp 10, to the receptacle 11 and to the busses 16 and 17, and in my system, these busses are connected to the ophthalmometer, to the sterilizer and to the test cabinet carried by the stand through 70 wires 18, 19 and 20, respectively.

The busses 16 and 17 are also connected to the primary of a transformer 21, through an alternative connection depending upon whether the line current is alternating or direct. The busses 16 and 17 are connected by wires 22 and 23 to contacts 24 and 25 of a suitable two-way switch 8, while the primary of the transformer is connected by wires 26 and 27 to the contacts 28 and 29 of 85 the switch. If the line current is alternating the switch connects contacts 24 and 25 with contacts 28 and 29 directly, as shown by the full lines, while if the line current is direct, the said contacts are connected 90 through the contacts 24' and 25' of a rotary converter 30.

The ratio of the illustrated transformer is such that the line voltage will be stepped down to $15\frac{5}{10}$ volts on a secondary line connected to the two end turns or taps 31 and 32. Between these two end taps are eleven intermediate taps having a potential varying from $2\frac{5}{10}$ volts to $14\frac{5}{10}$ volts. The terminals of the twelve taps from $2\frac{5}{10}$ volts to 100 $15\frac{5}{10}$ volts are arranged in an arc and a pivoted switch member 33 is arranged to contact successively with all of the tap terminals, as well as with an additional contact 34 which is not connected to the secondary of the 105 transformer and, hence, has zero voltage. In the latter position, therefore, the switch member is in "off" position.

The pivoted switch member 33 is connected by wire 35, switch 36 and wire 37 to 110

- one binding post 38 of a cautery connection, the other binding post 39 of the cautery connection being attached by wire 40 to the lead 41 from the end tap 31 of the secondary of the transformer. It will, therefore, be seen that by adjusting the pivoted switch member 33, any one of the twelve selected voltages may be supplied to the cautery connection.
- 10 For the low voltage instruments a pair of low voltage busses 42 and 43 are provided. As shown, the voltage supplied to these busses is $2\frac{5}{16}$ volts, which is a safe and sufficient voltage for the ordinary scopes used for optical examination purposes. The bus 42 is connected to the end tap 31 by the wire 41, while the bus 43 is connected to the $2\frac{5}{16}$ volt tap by wire 44, rheostat 45 and wire 46. It will, therefore, be seen that 15 while the maximum difference in potential between the two busses 42 and 43 is $2\frac{5}{16}$ volts, this potential difference may be reduced as desired by the manipulation of the rheostat 45.
- 20 25 As shown, three jacks 47, 48 and 49 are connected across the busses 42 and 43, the one terminal by conductors 50, 51 and 52, respectively, and the other terminal by the leads of a retinoscope 53 and ophthalmoscope 54 and a transilluminator 55, respectively. The construction of the said jacks is illustrated more particularly in the said pending application Serial No. 673,728, where it appears that the jacks close as the instruments 30 35 are withdrawn and are automatically opened as the instruments are inserted in their sockets in the top of the cabinet, suitable retractors being provided for the cables within the cabinet. The voltage across the busses 42 and 43 may be indicated by a 40 voltmeter 56.
- In addition to the jacks 47, 48 and 49, my system also provides two binding posts 57 and 58 for special scopes requiring $2\frac{5}{16}$ volts or less, the former binding post being connected to the wire 46 and the latter binding post being connected to bus 42 through switch 59.
- 45 I have also made provision, in accordance 50 with my invention, for the connection of a tracer lamp 60 which requires higher voltage than the low voltage instruments. As shown, I supply $6\frac{5}{16}$ volts to a bus 61 which is connected by wire 62 to the $6\frac{5}{16}$ volt tap from the secondary of the transformer. 55 This tracer lamp also has a jack 63 which is automatically opened by the insertion of the tracer lamp handle. One terminal of the jack is connected by the conductor 64 to the bus 42, while the other terminal is connected to the bus 61 through the tracer lamp and its cables which are also supplied with suitable retractile means within the cabinet.
- 60 65 It is obvious that various modifications in

the details and arrangement of parts, herein described and illustrated for the purpose of explaining the nature of the invention, may be made by those skilled in the art within the principle and scope of the invention, as 70 expressed in the appended claims.

I claim:

1. A wiring system for an ophthalmological apparatus comprising a source of line current, a pair of low voltage busses, a transformer having its primary connected to the source of line current, a plurality of spaced taps for the secondary of the transformer, a movable switch member adapted to contact successively with the terminals of the several taps, an instrument connection having one terminal connected to the switch member and the other terminal connected to one of the end taps, connections for the low voltage busses across two selected taps, and instrument leads connected across the low voltage busses. 75 80 85

2. A wiring system for an ophthalmological apparatus comprising a source of line current, a pair of low voltage busses, a transformer having its primary connected to the source of line current, a plurality of spaced taps for the secondary of the transformer, a movable switch member adapted to contact successively with the terminals of the several taps, an instrument connection having one terminal connected to the switch member and the other terminal connected to one of the end taps, connections for the low voltage busses across two selected taps, an adjustable resistance in the connections of the low voltage busses, and instrument leads connected across the low voltage busses. 90 95 100

3. A wiring system for an ophthalmological apparatus comprising a source of line current, a pair of low voltage busses, a transformer having its primary connected to the source of line current, a plurality of spaced taps for the secondary of the transformer, a movable switch member adapted to contact successively with the terminals of the several taps, an instrument connection having one terminal connected to the switch member and the other terminal connected to one of the end taps, connections for the low voltage busses across two selected taps, instrument leads connected across the low voltage busses, another bus connected to a selected tap, and instrument leads connected across said additional bus and one of the pair of low voltage busses. 105 110 115

4. A wiring system for an ophthalmological apparatus comprising a pair of high voltage busses adapted for connection to a source of line current, a pair of low voltage busses, a transformer having its primary connected to the high voltage busses, a plurality of spaced taps for the secondary of the transformer, a movable switch member adapted to contact successively with 120 125 130

20

25

- the terminals of the several taps, an instrument connection having one terminal connected to the switch member and the other terminal connected to one of the end taps,
5 connections for the low voltage busses across two selected taps, instrument leads connected across the low voltage busses and connections for an optical testing instrument to the high voltage busses.
10 5. A wiring system for ophthalmological apparatus comprising a pair of high voltage busses adapted for connection to a source of line current, a pair of low voltage busses, a transformer, a rotary convertor, means for connecting the primary of the
15 transformer to the high voltage busses se-

lectively either directly or through the rotary convertor, a plurality of spaced taps for the secondary of the transformer, a movable switch member adapted to contact successively with the terminals of the several taps, an instrument connection having one terminal connected to the switch member and the other terminal connected to one of the end taps, connections for the low voltage busses across two selected taps, and instrument leads connected across the low voltage busses.

In witness whereof, I hereunto subscribe my signature.

GILBERT S. DEY.
